UNITED STATES PATENT OFFICE.

RICHARD MAX EATON, OF NIAGARA FALLS, NEW YORK, ASSIGNOR TO NIAGARA SEARCHLIGHT COMPANY, INC., OF NIAGARA FALLS, NEW YORK, A CORPORATION OF NEW YORK.

FOCUSING HAND SEARCHLIGHT.

Application filed September 11, 1924. Serial No. 737,090.

This invention relates to portable electric lamps and one of its objects is to provide a lamp capable of producing a steady continuous light or a series of flashes, as may be desired, the light being controlled by novel means dispensing entirely with the usual push-button or sliding switches, eliminating occasional premature or accidental lighting, the unsightliness of such projecting parts and the expense of their construction.

A further purpose is to produce a hand lamp having a flexible bumper to protect the bulb from shock and damage due to falls, blows, rough handling and the like, the bulb being provided with an enclosed reflector whereby its surface is efficiently protected from handling, dirt and injury.

Another aim is in the provision of a lamp capable of having its light diffused or focused at will, the reflector lens and bonnet shell being united and operative as an integral body with respect to the main portion of the lamp and its bulb.

Still other objects are to provide extra bulb carrying compartments without increasing the length or diameter of the body; in the simplicity of construction, which includes a minimum number of parts, and in the ease of manipulation of the lamp.

These and other important objects are accomplished by the novel construction, combination and arrangement of parts hereinafter described and shown in the accompanying drawing, forming an essential portion of this disclosure, and in which:

Figure 1 is a side elevational view of an electric lamp made in accordance with the invention.

Figure 2 is an enlarged longitudinal sectional view of the front portion of the same.

Figure 3 is a similar view of the rear portion thereof.

Figure 4 is a bottom plan view of the lamp casing cover, parts being broken away to show the construction.

Figure 5 is a top plan view of the bulb support.

Figure 6 is a bottom plan view of the contact carrier attached to the lower side of the bulb support.

In common with electric lamps of the flash light type in general, the main body or casing 10 is composed of a metallic cylinder en-

larged at its rear portion 11 and provided with rolled screw threads 12, the interior of 55 the cylinder loosely containing one or more battery cells 13.

A cover, indicated generically by the numeral 14, consists of a resilient disc 15 having a beaded edge 16 which may be 60 knurled or formed into a polygonal shape as shown, and from which extends an annularly flanged portion 17, provided with screw threads 18 suited to engage over the corresponding threads 12 at the rear end of the 65 casing.

Contained within the cover 14 is a conically wound spiral spring 19, its lowermost convolution fitting the recess within the cover element 16, and its smaller, uppermost 70 coil is clamped between two dielectric washers 20 having between them a fibre plate or washer 21 in contact with the end of the coil and held rigidly by a metallic grommet or eyelet 22 passing through the coil and washer, the ends of the grommet acting as contacts, one of which is held by the action of the spring 19 against the contact at the end of the battery cell 13; the other end of the grommet makes electrical contact with the 80 cover disc 15 when the cover is adjusted by the screw threads for that purpose.

An inturned groove 23, formed in the disc 15, acts as a clip to engage one of the coils of the spring 19 when pressed thereagainst, 85 making a slight snapping sound, and being also perceptible to the touch of an operator, when exerting pressure against the disc to cause electrical contact of the grommet between the cell and disc when a flash or flashes 90 only are desired, and the cover adjusted relatively to the casing to just prevent positive and fixed contact, the disc 15 yielding slightly under pressure to produce such effect.

The front end of the casing is also formed 95 with a similar screw thread 24 to engage on its exterior the correspondingly threaded portion 25 of a bonnet 26, having a bead 27 and thereafter an expanded shell portion 28 having at its upper edge a spun beading 29.

A tongue 30 is sheared from the screw-threads acting as a spring detent or drag brake whereby the bonnet 26 is held uniformly tight upon the threads 24 by the frictional effect of the tongue.

A lens 31 is secured in the bead 29, the

lower peripheral edge of the lens resting on the outturned flange 32 of a reflector 33 having an annularly flanged central opening 34 through which the lamp bulb 35 extends into the space within the reflector 33.

The stem 36 of the bulb is fitted to a socket 37 formed integrally with a plate 38 having a downturned flanged edge 39 provided with screw threads fitted to engage within the threads 24, stops 40 being provided to limit the entrance.

A pair of dielectric washers 41 and 42, respectively upper and lower, are rigidly held to the underside of the plate 38, by two 15 or more grommets 43, and fixed in the upper washer 41 is a spring finger 44 extending partially across the axial opening in the washers, in the space between them, this finger being slightly deflected by contact 20 with the tip 45 of the bulb stem 36.

Also disposed between the washers 41 and 42 is a flange 46 from which depends a cup 47 the bottom of which is normally in contact with the contact on the battery cell 13, 25 and it will be understood that the flange 46 is at all times in electrical engagement with the finger 44, which may be bent by contact with the bulb stem to partially enter the top of the open cup 47.

Secured by one or more of the grommets 30 43 is a spring clip 48, its free portion 49 overhanging a depression 50 formed in the plate 38 and suited to receive a supernumerary bulb 35', horizontally together with its 35 stem, and it will be apparent that several such bulbs may be carried without enlarging or lengthening the lamp, the space occupied by these bulbs being otherwise not utilized.

It will now be apparent that the finger 44 40 acts as a buffer for the bulb in actual service and at the same time assures good electrical contact.

It will also be seen that the reflector 33 is entirely housed and not subject to the collection 45 of dust or finger marks as its surface is inaccessible.

As the reflector, lens and bonnet move as a unit and are readily adjustable relative to the lamp, which is held in an essentially 50 fixed position, the light from the bulb may be concentrated or focused as finely as desired, or spread widely by merely rotating the bonnet on the casing body, one or two turns effecting the change required, and such 55 relative turning is accomplished in a smooth and easy manner, without perceptibly loosening the parts, due to the spring tongue 30.

In operation, in place of actuating a switch, as usual set in the side of the casing, 60 the cover 14 is screwed on the casing until the grommet 22 makes contact with the disc 15 and end of the battery cell, current passing through the cover 14, casing or shell 10, plate 38 and socket 37 to the bulb, returning 65 by way of the stem tip 45, finger 44, flange

46 and cup 47 to the other pole of the battery.

If flashes rather than a continuous light is desired the cover is backed off slightly, 70 breaking the circuit, except as the disc is pressed inward by the operator to make contact of such duration as may be desired.

As changes of construction could be made within the scope of the invention, it is intended that all matter contained in the foregoing description or shown in the accompanying drawings shall be interpreted as 75 illustrative and not in a limiting sense except as limited by the claims.

Having thus described my invention, what 80 1 claim as new and desire to secure by Letters Patent, is:—

1. An electric lamp comprising a casing, a battery cell therein, a cover adjustably engaged on the rear end of said casing, 85 said cover having a resilient disc, a conically wound spiral spring in said cover, an insulated conductor carried by said spring to engage one pole of the battery cell, means for adjusting said cover to cause 90 the conductor to make contact with said disc, and a light bulb in electrical engagement with the opposite pole of the battery and said casing.

2. An electric lamp comprising a casing, 95 a battery cell therein, a cover adjustably engaged on the rear end of said casing, said cover having a resilient disc, a conically wound spiral spring in said cover, an insulated conductor carried by said spring to 100 engage one pole of the battery cell, means for adjusting said cover to cause the conductor to approach said disc, said disc yielding under pressure to make contact with said conductor, and a light bulb carried at 105 the opposite end of the casing in circuit therewith and with the opposite pole of said cell.

3. An electric lamp comprising a casing, 110 a battery cell therein, a cover adjustably engaged on the rear end of said casing, said cover having a resilient disc, a conically wound spiral spring in said cover, an insulated conductor carried by said spring to 115 engage one pole of the battery cell, means in said cover for retarding the action of said spring, means for adjusting the cover to cause said conductor to approach said disc, said disc being yieldable under pressure to complete contact, and a light bulb 120 in circuit with the opposite end of the battery cell and said casing.

4. An electric lamp having an adjustable bonnet, a reflector in the bonnet, a light bulb projecting into the reflector, a concavo-convex lens forming a closure for the reflector, a beading on said bonnet fixedly engaging the reflector and lens, a cap adjustable on the opposite end of said lamp, 125 the central portion of the end of said cap 130

being resilient, and a spring supported, insulated contact carried by said cap controlling the circuit to said bulb.

5. An electric lamp having a casing screw-threaded at its outer end, a bonnet adjustably engaged thereon, a reflector having a central opening, a bulb fixed in the casing to extend into the opening in said reflector, a concavo-convex lens covering 10 said reflector, a bead on said bonnet to secure the reflector and lens, and a spring tongue sheared from the casing to act as a friction brake for said bonnet.

15. An electric lamp having a casing screw-threaded at its outer end, a bonnet adjustably engaged thereon, a reflector having a central opening, a tongue sheared in the thread of said casing to frictionally engage the threads of the bonnet, a bulb 20 fixedly carried by said casing to project into the reflector, and a lens clamped by said bonnet over the reflector.

25. An electric lamp having a bonnet, a reflector and lens fixed in said bonnet, a light bulb, a casing in which said bulb is fixed, means for adjusting said bonnet, reflector and lens as a unit relatively to said bulb whereby the light may be focused or diffused at will, and a resilient prong 30 formed in said casing to frictionally retain said bonnet in adjustment.

35. An electric lamp comprising a casing, a battery cell therein, a cover engaged on the rear end of said casing, a bonnet adjustably engaged on the front end of the casing, a reflector and lens fixed in said bonnet, a support plate fixed in the front

end of said casing, a light bulb removably engaged in said plate, said plate having one or more depressions in its outer surface adjacent said bulb, a clip fixed on said plate to retain a supernumerary bulb in the depression, and controllable means for making or breaking circuit connections between the cell and fixed bulb. 40 45

9. In an electric lamp, a bulb supporting means comprising a plate having a raised socket to receive the stem of the bulb, means on said plate to carry supernumerary bulbs in a reclining position, said means including 50 depressions and spring clips to engage the stems of said bulbs, means for removably engaging said plate to the body of the lamp, and insulated means carried by said plate to conduct current to the socket carried bulb, said means including a resilient element. 55

10. In an electric lamp, a bulb supporting means comprising a plate having a raised socket to receive the stem of the bulb, said plate being removably attached to the front end of the lamp casing, a battery cell in the lamp casing, a pair of dielectric washers fixed to the underside of said plate, a spring finger fixed between the 60 65 juxtaposed washer to extend into the opening therein and make contact with the stem tip of the bulb, and a cup having a flange disposed between said washers in contact with said finger, said cup being normally 70 in engagement with said cell.

This specification signed this 8th day of September, 1924.

RICHARD MAX EATON.
